BOILER PRESSURE CONTROL APPARATUS

Jesse B. Snyder, Tacoma, Wash.

Application March 23, 1936, Serial No. 70,220

2 Claims. (Cl. 236—26)

This invention relates to pressure control devices and especially to devices adapted to automatically keep the pressure of a boiler at a uniform figure by controlling the draft of the boiler.

It has been the practice to attempt to control the steam pressure of the boiler by causing a pressure-controlled apparatus to itself actuate the boiler damper, whereby the draft is controlled, but it is evident that, in such a case, the only actuating force would be the difference of pressure between the balanced or neutral condition of the instrument and the subnormal pressure thereof at the time, in other words, when the normal pressure is supposed to be say 8 pounds in the boiler and it drops to 7 pounds, then only one pound is available to actuate the damper. For this reason such controls are of very little value in low pressure boilers, such as are used in many heating plants.

In order to overcome this objection I have devised the following described mechanisms, the primary object being to provide means whereby the boiler draft may be operated by an independent unvarying source of power which is, in turn, controlled by the boiler pressure in such a manner that the full effect of said power is applied at once on the slightest variation of the pressure in the boiler, this action being so sensitive that, in practice, a variation of as little as a quarter of an ounce will cause the damper to be opened or closed. A further object is to provide such a control as may be applied to standard mechanism at present in use, with but little alteration thereto.

I attain these and other objects by the mechanisms, devices and arrangements illustrated in the accompanying drawing, in which—

Fig. 1 is a front elevation of a boiler equipped with my apparatus, showing the parts in their normal positions when the pressure is at normal; Fig. 2 is a longitudinal section of the "air motor" which actuates the boiler damper, showing it in the act of opening, or holding open, the damper to increase the draft through the boiler; Fig. 3 is a side elevation of my improved means for controlling the "air motor", parts being broken away to reveal the construction and showing the position of the parts when the boiler is below its normal pressure; and Fig. 4 is a similar view of a modified form of such apparatus, showing the parts in the positions taken thereby when the pressure in the boiler is normal.

Similar numerals of reference refer to similar parts throughout the several views.

Referring to the drawing it will be seen that the boiler 1 is provided with a draft control or damper 2, of the usual form, adapted to be opened by being raised.

5

Pressure-sensitive apparatus

The steam from the boiler enters the bellows chamber 3 of the usual construction and containing a metallic bellows 4 (Fig. 3) therein, said bellows registering by its upward movement the pressure within the boiler 1. The movement of the bellows 4 is communicated to a rocker 5, pivot at 6 to the upper side of the chamber 3, and this rocker 5 is provided with an arm 7 on which a weight 8 is adjustably mounted to counteract the action of the steam pressure on the bellows 4. The weight 8 is adjusted so that it is raised by the pressure in the boiler when such pressure has reached its desired predetermined normal. The arm 7 operates between two adjustable stops 9 and 10. The rocker 5 is provided with an extension 11, which engages the air-control apparatus, as hereinafter described.

Air motor

25

Referring, now, to Fig. 2, the "air motor" comprises a dish 12, having a rubber or otherwise flexible diaphragm 13 secured thereto; a supply of compressed air being admitted to or released from the space between the dish 12 and the diaphragm 13 by means of the pipe 14. A saucer 15 rides on the rubber diaphragm 13 and is pivotally connected to an arm 16, pivoted at 17 to the air motor frame. This arm 16 is connected at one end to the damper 2 by means of a chain 18, and the action of the air under the diaphragm 13 is opposed by a compression spring 19 mounted between the other end of the arm 16 and the air motor frame. The upward swing of the arm 16 is limited by the adjustable stop 20.

30

35

40

Air control apparatus

A supply of compressed air, say at 15 pounds per square inch pressure, is provided by a suitable air compressor, not shown, and is delivered by a supply pipe 21 to the air control apparatus. This apparatus comprises a main body 22 having a cavity divided, by a wall 23 and a rubber diaphragm 24, into three chambers 25, 26 and 27. The wall 23 has a central hole 28 therethrough, said hole 28 providing a seat for the floating valve 29. The valve 29 is secured to and passes through another rubber diaphragm 30, which forms the outer closure of the chamber 27, and 50 55

has a stem which passes loosely through the hole 28 in the wall 23. The valve 29 has a central hole 31 passing entirely through it and the said stem. The inner orifice of the hole 31 is adapted 5 to be engaged and closed by the first said rubber diaphragm 24. A passage 32 leads from the supply pipe 21 to the chamber 27 and a small by-passage 33 connects the said passage 32 with the chamber 25. The central chamber 26 is connected by a passage 34 to the pipe 14 which leads 10 to the air motor. Another by-passage 35 leads from the chamber 25 to a leakage orifice 36. This orifice 36 is adapted to be closed by a finger 37 pivoted at 38 to the frame. The said finger 15 37 is held against the said orifice 36, to close it, by a weighted arm 39 as shown, or by any other equivalent structure. The end of the above-described extension 11 on the rocker 5 is hooked to engage the said finger 37 to move it away 20 from the orifice 36 when the pressure in the boiler is raised to normal and releases the said finger 37 to close the said orifice 36 when the pressure is slightly below normal. It will be understood that the by-passages 33 and 35 and the 25 orifice 36 are of very small diameters.

Variation

Referring now to Fig. 4 it will be seen that the intermediate finger 37, above described, is dispensed with in this alternate construction, the extension 11 acting directly on the orifice 36 to open or close it in similar manner as above described.

Operation

35 The action of my apparatus is briefly described as follows:—When the boiler pressure is at normal (Figs. 1 and 4), the compressed air travels by the pipe 21 and the passage 32 into the chamber 27 but cannot escape therefrom through the valve seat in the wall 23 and escapes or leaks 40 through the by-passage 33, chamber 25, by-passage 35 and the open orifice 36, while whatever air may be in the air motor escapes from between the dish 12 and the diaphragm 13 by the 45 pipe 14, passage 34, chamber 26 and hole 31 through the valve 29; the rubber diaphragm 24, being under substantially equal pressure on both sides, is straight and out of contact with the valve 29. But, the moment that the orifice 36 50 is closed by the finger 37, or the extension 11, the pressure in the chamber 25 is built up, thus bulging the diaphragm 24 and closing the hole 31 and pushing the valve 29 to open the valve 55 seat in the wall 23 (Fig. 3), thus permitting the direct air pressure to pass from the pipe 21 to the chamber 27 by the passage 32, thence out

through the hole 28 in the wall 23, into the chamber 26, thence by the passage 34 and the pipe 14 direct to the air motor; thus raising the saucer 15 and arm 16, and the damper 2 of the boiler. As soon as the boiler pressure is built up to normal, the finger 37, or the extension 11, opens the leakage orifice 36 allowing the escape of the air pressure from the air motor and returning it to normal under the action of the spring 19, and the damper 2 is thus permitted 10 to close under the action of gravity.

15 It is, of course, to be understood that many variations may be made in the details of construction of the several instrumentalities illustrated and described in the above specification, without departing from the spirit of my invention as outlined in the appended claims.

Though the several instruments are shown as distinct structures, it is to be understood that they may be redesigned and incorporated in 20 a single structure, the instruments shown and described being composed of several agencies at present in use and modified to accomplish the ends of this invention.

Having, therefore, described my invention, 25 what I claim and desire to secure by Letters Patent, is:—

1. In boiler pressure control apparatus, including a damper adapted to be opened and closed to control the boiler draft, comprising a 30 boiler pressure-sensitive apparatus; an air motor connected to said damper and adapted to open it when compressed air is admitted thereto; an air control apparatus connected between a source of air pressure and the said air motor, said air 35 control apparatus being provided with an air leakage orifice; and a pivoted finger adapted to normally close said leakage orifice, but adapted to be engaged by said pressure-sensitive apparatus to open said leakage orifice when the pressure reaches a predetermined normal in the pressure-sensitive apparatus.

2. In boiler-pressure control apparatus including a fire control means; a boiler-pressure sensitive apparatus; an air motor connected to said fire control means and adapted to operate to increase the fire when compressed air is admitted thereto; an air control apparatus connected between the source of air pressure and said air motor, said air control apparatus being provided with an air leakage orifice; and a pivoted finger adapted to normally close said leakage orifice, but adapted to be engaged by said pressure-sensitive apparatus to open said leakage orifice when the pressure reaches a predetermined normal in the pressure-sensitive apparatus.

JESSE B. SNYDER.
